United States Patent Office

Des. 206,958

Patented Feb. 14, 1967

206,958

JUG

Victor F. Anderson, Wenonah, N.J., assignor to Shell Oil Company, New York, N.Y., a corporation of Delaware

Filed Apr. 1, 1966, Ser. No. 1,738

Term of patent 14 years

(Cl. D58—5)

FIG. 1

FIG. 2

FIG. 4

FIG. 3

FIG. 5

FIG. 1 is a side elevation view of a jug showing my new design;

FIG. 2 is an elevation view displaced 45° from that of FIG. 1;

FIG. 3 is an elevation view displaced 90° from that of FIG. 2;

FIG. 4 is a top plan view; and

FIG. 5 is a bottom plan view thereof.

I claim:

The ornamental design for a jug, as shown.
